United States Patent Office

Des. 185,150
Patented May 12, 1959

185,150

BALL POINT PEN

Ray E. Hulbert, Rockaway, N.J.

Application December 3, 1957, Serial No. 48,752

Term of patent 14 years

(Cl. D74—17)

Fig. 1.

Fig. 2.

Fig. 1 is a front elevational view of a ball point pen showing my new design, a portion of the chain being shown broken away for convenience of illustration; and Fig. 2 is a top plan view thereof.

I claim:

The ornamental design for a ball point pen, as shown and described.
